UNITED STATES PATENT OFFICE

145,684

DESIGN FOR A SHOE OR SIMILAR ARTICLE

Evelyn Ziniti, New York, N. Y.

Application May 10, 1946, Serial No. 129,541

Term of patent 7 years

(Cl. D7—7)

To all whom it may concern:

Be it known that I, Evelyn Ziniti, a citizen of the United States of America, residing in New York, county of New York, and State of New York, have invented a new, original, and ornamental Design for a Shoe or Similar Article, of which the following is a specification, reference being had to the accompanying drawing, forming part thereof.

Fig. 1 is a front perspective view of a shoe or similar article showing my new design.

Fig. 2 is a front perspective view of the opposite side of the shoe seen in Fig. 1.

I claim:

The ornamental design for a shoe or similar article, substantially as shown.

EVELYN ZINITI.
